MEANS FOR WELDING

Alfred J. Lautmann, Detroit, Mich., assignor to
Iodent Chemical Company, Detroit, Mich., a
corporation of Michigan

Application August 27, 1943, Serial No. 500,201

2 Claims. (Cl. 219—4)

This invention relates to the sealing of filled metallic collapsible tubes, such as are used for tooth paste, cosmetics, and like commodities.

It has been the general practice after the filling of a collapsible tube is accomplished, which is done through the open bottom thereof, to flatten the tube so that its bottom wall portions are in juxtaposition with its free edges contiguous and then to fold these edges over upon themselves one or more times. The folded end then is secured by means of a clip of stiffer metal fastened thereto. This method of closing, which requires the addition of a clip, materially adds to the cost, and sometimes does not provide a good or hermetic seal for the tube bottom. The lack of a satisfactory seal frequently becomes objectionable in such instances for example, as during the handling, and particularly during shipping of collapsible tubes for sometimes the tubes are so jammed or deformed that the contents thereof may be forced outwardly through the folded bottom which may stain or destroy the desired appearance and serviceability of the tube or package therefor to such an extent as to make it unmerchantable.

Various efforts have been made to seal the juxtaposed edges by interfusion but such known instances involve costly machines, impractical clamping devices, and inefficient complicated sealing devices requiring an excessive amount of electric current.

It is, therefore, an object of the present invention to provide a novel machine which will close and hermetically seal a filled collapsible tube or the like entirely automatically.

Another object is to provide novel means on an automatic closing and sealing machine to effect a liquid and gas-tight joint in the nature of a hermetic seal at the closed bottom of collapsible tubes, which means is highly efficient in use and inexpensive to operate.

A further object is to provide a novelly constructed automatically actuated electric welding or interfusion device operable to effect continuous uniform welding of the bottom edges of a collapsible tube or the like.

Yet another object is to provide a welding device for use in an automatic tube closing machine which, while being entirely self-contained, will be operable dependently with operating mechanisms of such machine.

Another object is to provide a novel method of operation to hermetically seal the closed bot-

tom of a collapsible tube or the like so as to effect a liquid and gas-tight joint.

Other and further objects of the present invention will be apparent from the following description and claims and are illustrated in the accompanying drawings which, by way of illustration, show preferred embodiments and the principle thereof and which I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings,

Fig. 1 is a side elevational view of a known form of a closing and sealing machine embodying the features of the invention;

Fig. 2 is a plan view of the machine;

Fig. 3 is an end elevational view of the machine showing the timing gear mechanism housing removed;

Fig. 4 is an enlarged detail view in plan of the tube closing mechanism;

Fig. 5 is a side elevational view of the mechanism, shown in Fig. 4, taken substantially along line 5—5 of Fig. 2;

Fig. 6 is an enlarged front elevational view of an embodiment of the tube welding device;

Fig. 7 is an elevational view taken in a plane at right angles to the Fig. 6 disclosure, showing the tube conveyer chain and a part of the machine frame in section;

Fig. 8 is a sectional view taken substantially on line 8—8 of Fig. 6;

Fig. 9 is a sectional view showing the folding mechanism, taken substantially along line 9—9 of Fig. 2;

Fig. 10 is a view showing a fragment of a collapsible tube after its end has been hermetically sealed by welding;

Fig. 11 is another fragmentary view of the collapsible tube, showing its sealed end folded; and

Fig. 12 is a view similar to Fig. 6, showing a modified form of welding device.

The collapsible tubes 10 to be closed, sealed and folded, are filled through their open bottom, bottom side up, in a suitable machine wherein they are automatically conveyed in a step-by-step movement into successive stations of rest for the various operations required to effect the desired operations. A typical ma-

chine of this character is generally illustrated in Figs. 1, 2 and 3, inclusive. This machine includes a supporting frame 11 embodying legs 12 and a bed plate or top 13 upon which the various devices for operating on the tubes are mounted. The tubes 10 may be carried into these various devices or stations by any suitable mechanism such as an endless conveyor 14 consisting of interconnected links, each carrying a holder or cup 15 for supporting the tubes. The conveyor 14 travels longitudinally of the machine along suitable supporting guides 16 and 17 and is supported at its ends by sprocket wheels 18 and 19. The sprocket wheel 19 is driven to thereby drive the chain 14. As shown, the wheel 19 receives its driving force through a gear 21 mounted upon its shaft 22 and operatively associated in a manner to be described hereinafter with a suitable source of operating power.

The tube supporting cups 15 preferably are metallic or otherwise electrically conductive and they are spaced uniformly along the conveyor 14, at such distances apart as to properly position the tubes so that work may be performed on them simultaneously at each of the various operating stations. Certain of these operations require that the movement of the cups be momentarily retarded, consequently, means is provided to give the conveyor an intermittent movement, each movement being equal to the spacing.

To obtain the required intermittent movement of the conveyor, suitable drive mechanism is provided, which may be a conventional Geneva movement. As best illustrated in Figs. 1 and 3, this drive mechanism includes the gear 21 which meshes with a pinion 23 carried on one end of a stud shaft 24, the other end of which carries a slotted plate 25 constituting one element of the Geneva movement mechanism. A driving element 26 carried on a second stud shaft 27 includes a face plate 28 recessed as at 29 at one side of a roller 31 carried thereon. Upon rotation of the driving element 26, the roller 31 engages in one of the slots 32 of the plate 25 to rotate said plate a distance equal to the spacing between adjacent slots. During the interval of rest, movement of the conveyor and its drive mechanism is prevented in the well known manner by engagement of plate 28 with a recessed edge of the slotted plate 25.

The stud shaft 27 carrying the driving element 26 also carries a gear 33 movable with said element. This gear meshes with a gear 34 carried on a main shaft 35 extending longitudinally of the machine above the top plate 13 and journaled at and intermediate its ends in bearings 36. The longitudinal shaft 35 is driven by a spiral gear 36 (Fig. 9) meshing with a gear 37 securely mounted on a transverse shaft 38. The shaft 38 is driven through a clutch 39 having a driving connection by a belt 41 with a pinion 42 carried on a shaft 43 mounted below the top plate 13. The shaft 43 also carries a sprocket 44 which is operatively connected by a silent chain 45 with an electric motor 46, the operation of which may be controlled by a switch 47. Operation of the entire mechanism is controlled through the clutch 39 by a lever 48 extending beneath the top plate 13 and operable through a vertical shaft 49 to move an operating fork 51.

In use of the machine, the filled collapsible tubes 10 in the cups 15 are moved or carried over the length of the machine in a step-by-step

movement during which movement they are successively positioned beneath various units which first collapse or fish-tail the open upper end of the tube to dispose its walls at the end portion in juxtaposition and then weld or otherwise interfuse the juxtaposition edges of the tube. The tube end thus sealed may then be folded over in one or more folds to reinforce the tube bottom and protect the welded edge so as to prevent ultimate leakage resulting from the application of internal pressure.

The first step of closing the tube ends may be accomplished by any suitable mechanism. One form of mechanism for this purpose, best disclosed in Figs. 4 and 5, consists preferably of a pair of opposed reciprocable jaws 52 operatively connected for movement in unison to engage and squeeze the open end portion of the tube together tightly. Operation of the jaws may be effected through reciprocable movement of a slide 53 guided in a bearing block 54 carried on the top plate 13. The slide has a roller 55 at its rear-most end operatively engaged in an eccentric groove 56 in one face of a cam member 57 fixedly secured on the longitudinal main shaft 35. This mechanism is such that one complete rotation of the cam 57 in timed relation to the stop action of the conveyor 14 will move the jaws 52 through one cycle, that is, move them into their closed position and then their normal open position while the conveyor is at rest.

Obviously, some of the contents of the tube may be forced out of the collapsed end during the pressing operation, which excess material cakes upon the jaws and may hinder further operation. To remove this excess material, a suitable suction cup 58 may be mounted for vertical reciprocation above the clamp jaws 52 in a bracket 53. The cup is connected through a pipe 59 with a suitable source of negative pressure and is adapted to be moved downwardly immediately after the clamp jaws 52 have clamped the end of the tube so as to completely enclose the upper end of said clamped tube and effectively draw off any surplus material. Vertical reciprocation of the suction cup may best be obtained by providing a rack 61 on one side thereof which meshes with a pinion 62 operable through a rack 63 formed on the end of a spring controlled cam 50 actuated reciprocable plunger 64. A roller 65 carried on the rear end of the plunger 64 rides upon the circumferential face of the cam member 57 in which a recess 66 is provided. It should be obvious that during one complete revolution of the cam member 57, the roller 65 drops into the recess 66, thus rotating the pinion 62 to momentarily lower the suction cup 58.

It should be understood that the mechanism above described does not constitute novelty of the present invention and has been described only to the extent required to illustrate the operation of the present invention.

After the upper tube end has been flattened, the tube is carried, through further movement of the conveyor into the next stop station where further operations, later described, are effected. However, during movement of the collapsible tube between these two stations, the collapsed or flattened end is welded or otherwise interfused to provide a liquid and gas-tight joint at its edges in the nature of an hermetic seal. To this end, a novel welding or interfusion device, best shown in Figs. 6, 7 and 8 is provided on the machine. As shown, the top plate 13 of the machine carries an upwardly extending bracket 67 having a block

68 of suitable insulation material extending forwardly from its upper end provided on its forward end with a metallic plate 69. The plate 69 is suitably bifurcated or otherwise formed at one end to receive the upper end of a cylindrical holder 71 pivotally secured thereto by a pin 72. The holder 71 provides a mounting for an electrode preferably in the form of a carbon stick 73 which may readily be adjusted in length upon manipulation of set screws 74 so as to dispose its free pointed end substantially in the path of but below the top plane of the upper juxtaposed edges of the closed tube 10 so as to be engaged thereby when said tube moves therebeneath. A spring 75 is provided to create a firm yieldable contact between the electrode 73 and the upper end edges of the tube for a purpose to be more fully understood as the description of the welding operation proceeds.

The base of the bracket 67 includes a block 76 of suitable insulation material to provide a support for one end of a horizontally disposed conductor shoe 77, the other end of which is supported in a similar insulation block 76 supported in a bracket 78. As best shown in Fig. 8, the shoe 77 has rearwardly extending pins 79 extending through the respective installed supports and each pin is surrounded by a tension spring 81 so that the shoe normally is urged forwardly away from its supports whereby it is disposed in the path of the cup 15 carried by the conveyor 14. Consequently, as a cup 15 advances to carry the tube therein into contact with the electrode 73, it initially contacts the shoe and tensions the springs 81 whereby a firm sliding contact is maintained between the shoe and cup. Both the shoe 77 and the electrode 73 are suitably connected, as shown diagrammatically in Fig. 6, with any available source of electric current, such as for example, the storage battery 82. It should be evident at this time that when the metallic cup 15 makes contact with the shoe 77, during its movement along the machine, the electric current enters said cup and passes into the metallic collapsible tube 10. As soon as the juxtaposed edges of the flattened tube end contact the end of the carbon electrode 73, the circuit is complete and because of the high resistance of the carbon electrode 73, the material of the tube is melted so as to cause interfusion of the juxtaposed edges as the tube moves past the electrode.

It is important that a uniform interfusion or welding be effected and to this end it is essential that movement of the conveyor and pressure of the electrode on the work during the welding operation be constant and that the flow of current be uniform. To be otherwise may result in a weak spot in the welding because insufficient heat or excessive heat applied at any one point will result in non-uniform melting. For example, should an excessive amount of current momentarily be applied, there will be an excessive melting of the tube walls and as a result a weak spot will develop. Similarly, should less than the required current be applied, the fusion may be incomplete thus leaving a weak and perhaps a broken spot. Likewise, should movement of the conveyor or pressure of the electrode be irregular, too much or too little heat will be applied at certain points along the welded seam. The result is the same, an imperfect joint. It is, therefore, desirable but by no means essential that a storage battery be utilized as the source of supply because of the even flow of current obtained. The welding device herein disclosed is particu-

ly designed to maintain a uniform pressure upon the work so that a liquid-tight and gas-proof hermetic seal is formed on the flattened end of the tube. It further is advantageous and consequently inexpensive to use because current is used only while welding is being effected, the circuit being interrupted when the tube passes out from beneath the electrode 73.

Movement of the welded tube from beneath the electrode 73 carries it into the stop-position or station which in the instant disclosure consists of suitable automatically operable conventional mechanism for folding the flattened and welded end portion of the tube over upon itself either one or two times to protect the welded edge and further reinforce the tube end. As best illustrated in Fig. 9, the folding mechanism is actuated by two cams 83 and 84 fixedly secured upon the transverse shaft 38. The cam elements 83 and 84 are each provided with circumferential grooves 85 and 86 respectively, each of which co-acts with pins 87 and 88 respectively, on slidable bearing blocks 89 and 91 respectively, carried in a bracket 92 mounted on the top face of the plate 13. The cams 83 and 84 are arranged so that upon being rotated in unison, they move the blocks 89 and 91 towards each other in timed relation to the stop period of the tube conveyor 14. When the blocks move inwardly towards each other, an anvil 93 mounted on one block is carried into contact with one side of the flattened tube end which is backed up by one arm of a bell crank 94 carried on the other block. This contact of the anvil 93 with the flat tube end limits forward movement of said anvil. The anvil is, however, yieldably mounted in the block 91, consequently, said block continues forwardly independently of the anvil 93 to carry a roller 95 mounted on the downwardly turned end of an associated arm 96 against the upwardly extending end portion of the flattened tube end, folding said end portion downwardly against the top of the bell crank 94 as illustrated.

The parts are then momentarily withdrawn into their initial apart position by the cams. Continued rotation of the cams again moves the blocks 89 and 91 with their complementary parts inwardly towards each other, whereupon the free end of the bell crank arm 94 engages the initially bent-over portion of the collapsible tube to press it down firmly into tight engagement with the flattened tube end. During this final folding operation, the flattened end of the tube is backed up by the plunger 93. If a double fold of the kind illustrated in Fig. 11 is desired, the folding mechanism described and illustrated in Fig. 9, may be duplicated by providing such mechanism on each side of the transverse shaft 38, as generally illustrated in Fig. 2, the spacing between said folding devices being equal to the spacing between the holders carrying the collapsible tubes.

It will be observed that the welded edge of the folded tube is adequately protected and reinforced against inadvertent breakage and subsequent leakage. It should be understood, however, that the welding operation, when properly accomplished in the manner described herein, will result in a seam that will resist all normal pressures or forces tending to rupture the collapsible tube inasmuch as the welded seam will be as strong as and perhaps stronger than the material forming the tube.

Although a preferred embodiment of the welding device has been described hereinafter, it

should be understood that other types of devices, which will serve with equal satisfaction to provide a liquid and gas-tight hermetic seal at the tube end, may be employed. Such a modification is illustrated in Fig. 12 wherein the electrode holder 71a has mounted thereon, but insulated therefrom, two wipers 97 and 97a having a common connection with one terminal of the electric circuit. The other terminal of the electric circuit is connected to the holder 71a as before. In operation the collapsible tube 10 is carried forward by the conveyor 14 so that its flattened end edges initially contact the wiper 97a. Continued movement carries the edges into contact with the spring pressed electrode 73 whereupon the circuit is completed through wiper 97a, the tube 10 and the electrode 73 so as to heat the electrode and melt and interfuse the juxtaposed tube edges in contact therewith. As the tube continues its movement relative to the electrode 73, the wiper 97a finally moves off of the edge of the tube. The circuit is not broken by this disconnection because the other wiper 97 is now contacting the tube edges. Accordingly, the circuit is closed and the electrode 73 becomes effective to weld the tube ends immediately upon contact being made between the electrode and the tube edges, which contact is maintained until the electrode passes off of the opposite end of said edge. In other respects the welding device described is like that previously described and shown in Fig. 2 and like numbers identify corresponding parts. It should be obvious, however, that this form of construction may be simpler and less expensive in that a separate

yieldably mounted shoe is not required and that the cups or holders 15 supporting the tubes need not be of metal or of any other conductive material.

5. What I desired to claim as new and secure by Letters Patents is:

1. In a machine for sealing the collapsed end of a filled metallic tube having a metallic carrier for said tubes, a bracket on said machine, a shoe mounted on and insulated from said bracket connected to one terminal of an electric circuit, an electrode mounted on and insulated from said bracket and connected to the other terminal of said circuit, means to move said carrier into contact with said shoe and carry the collapsed end of the tube into contact with the electrode to close the circuit so as to heat the electrode and melt and interfuse said end along the line of contact with said electrode.
- 10 2. In a machine for sealing the collapsed end of a filled metallic tube having a metallic carrier for said tubes, a bracket on said machine, a shoe yieldably mounted on and insulated from said bracket connected to one terminal of an electric circuit, a carbon electrode yieldably mounted on and insulated from said bracket and connected to the other terminal of said circuit, means to move said carrier into firm contact with said shoe and carry the collapsed end of the tube into firm contact with the electrode to close the circuit so as to heat the electrode and melt and interfuse said end along the line of contact with said electrode.
- 15 3. In a machine for sealing the collapsed end of a filled metallic tube having a metallic carrier for said tubes, a bracket on said machine, a shoe yieldably mounted on and insulated from said bracket connected to one terminal of an electric circuit, a carbon electrode yieldably mounted on and insulated from said bracket and connected to the other terminal of said circuit, means to move said carrier into firm contact with said shoe and carry the collapsed end of the tube into firm contact with the electrode to close the circuit so as to heat the electrode and melt and interfuse said end along the line of contact with said electrode.
- 20 4. In a machine for sealing the collapsed end of a filled metallic tube having a metallic carrier for said tubes, a bracket on said machine, a shoe yieldably mounted on and insulated from said bracket connected to one terminal of an electric circuit, a carbon electrode yieldably mounted on and insulated from said bracket and connected to the other terminal of said circuit, means to move said carrier into firm contact with said shoe and carry the collapsed end of the tube into firm contact with the electrode to close the circuit so as to heat the electrode and melt and interfuse said end along the line of contact with said electrode.
- 25 5. In a machine for sealing the collapsed end of a filled metallic tube having a metallic carrier for said tubes, a bracket on said machine, a shoe yieldably mounted on and insulated from said bracket connected to one terminal of an electric circuit, a carbon electrode yieldably mounted on and insulated from said bracket and connected to the other terminal of said circuit, means to move said carrier into firm contact with said shoe and carry the collapsed end of the tube into firm contact with the electrode to close the circuit so as to heat the electrode and melt and interfuse said end along the line of contact with said electrode.
- 30 6. In a machine for sealing the collapsed end of a filled metallic tube having a metallic carrier for said tubes, a bracket on said machine, a shoe yieldably mounted on and insulated from said bracket connected to one terminal of an electric circuit, a carbon electrode yieldably mounted on and insulated from said bracket and connected to the other terminal of said circuit, means to move said carrier into firm contact with said shoe and carry the collapsed end of the tube into firm contact with the electrode to close the circuit so as to heat the electrode and melt and interfuse said end along the line of contact with said electrode.

ALFRED J. LAUTMANN.
